UNITED STATES PATENT OFFICE.

CHARLES L. VAN INWAGEN, OF RUTHERFORD, NEW JERSEY, ASSIGNOR TO WESTERN ELECTRIC COMPANY, INCORPORATED, OF NEW YORK, N. Y., A CORPORATION OF NEW YORK.

TICKET HOIST.

Application filed March 17, 1921. Serial No. 453,102.

To all whom it may concern:

Be it known that I, CHARLES L. VAN INWAGEN, a citizen of the United States, residing at 206 Sylvan Street, Rutherford, 5 in the county of Bergen, State of New Jersey, have invented certain new and useful Improvements in a Ticket Hoist, of which the following is a full, clear, concise, and exact description.

- 10 This invention relates to a ticket hoist for use with a mechanical ticket distributing system, such as is employed in telephone exchanges for sending information or instructions from one operator to another.
- 15 The object of this invention is to provide a method and means whereby an article carrier may be started, by an operator, from a position inaccessible to the operator and maintained in motion thereafter without the 20 attention of the operator.

The ticket hoist comprises a casing which is attached to the main guides of the ticket distributing system. Pivottally mounted in one end of the casing is a shaft to which 25 is fixed a hoist arm and on which is rotatably mounted a cam wheel which makes engagement with the hoist arm. In the other end of the casing is a shaft to which two nearly parallel levers are fixed. The 30 lower end of one lever is connected to the periphery of the cam wheel by means of a link consisting of a helical spring which has a tape connected to each end. The other lever is connected to a bell crank and operating lever. The moment about the shaft due to the weight of the hoist arm in certain positions is balanced by the moment 35 due to the pull on the cam wheel transmitted through the spring. When the hoist arm is 40 in horizontal position, it is locked in that position by means of a dog which is pivoted to the casing. The lowering or raising of the hoist arm is accomplished by adjusting the operating lever so as to decrease or increase 45 the moment about the cam axis due to the pull of the spring so that it either underbalances or over-balances the moment created by the weight of the hoist arm. The cam wheel is so designed that as the hoist 50 arm swings down or up, the distance from the cam axis to the point through which the force exerted by the spring acts, is decreased or increased so as to decrease or increase 55 the moment due to the spring. The release of the hoist arm from the dog is

effected when the operating lever is adjusted to alter the tension of the spring.

This invention will be more clearly understood from the following detailed specifications and accompanying drawings.

Figure 1 is a side elevation of the ticket hoist showing it attached to the guides. Figure 2 is an end elevation. Figure 3 is a top view showing how the guides connect. Figure 4 is a cross section through the casing showing the locking device. Figure 5 is a cross section through the casing, showing the cam wheel and the connecting tapes. Figure 6 is a horizontal cross section. Figure 7 shows the operating lever.

A system of main guides 10 has a track 11 attached thereto on which a trolley 12 travels. Trolley 12 has an arm 21 which extends across the guides 10. A casing 13 is attached to the guides 10 by any suitable means. In one end of the casing 13, a shaft 14 is pivotally mounted. Fixed to the shaft 14 is a bracket 16. A cam wheel 15 is rotatably mounted on shaft 14. A hoist arm 17 is riveted to the bracket 16 by means of 20 rivets 18. This hoist arm 17 is made from a guide which is of the desired length and is provided with a ticket holding means 19 at its free end. Ticket 20 is shown in the ticket holding means. An axle 22 is pivotally mounted in the casing and has a lever 23 fixed thereto. The lever 23 has a projection 24 at its lower end and also a hole 30 therein. Carried on the projection 24 is a screw fastening means 25 by which tape 26 is attached to the lever 23. The projection 24 is made in the shape of an arc of a circle so that as the tape 26 is brought into engagement with its outer surface it does not receive any sharp bends which would tend 35 to shorten the life of the tape. A helical spring 27 forms the connecting link between tapes 26 and 28. Tape 28 is connected to the cam wheel 15 by a screw fastening means 29. Projecting through the 40 hole 30 in the lever 23 is a rod 31 which is connected to dog 32 by means of the knuckle joint 33. The length of the rod 31 between lever 23 and knuckle joint 33 may be varied 45 by means of nut 36. The dog 32 is pivotally connected to the casing 13 by means of an eccentric screw 34. When the hoist arm 17 is in its horizontal position the dog 32 50 engages with the projection 35 which is integral with the U shaped portion 36 of the 55

bracket 16. Fixed to the axle 22 is a second lever 37 which has an opening therein. Projecting through the opening in the lever 37 is a rod 38 which has a thread portion 39 and a nut 40 thereon which connects the rod 38 to the lever 37. The other end of the rod 38 is connected to one arm of a bell crank 41 which is pivotally mounted on the frame of the guides 10 by means of screw 42. The other arm of the bell crank 41 is connected to an operating lever 44 by means of rod 43. The operating lever 44 consists of an offset rod mounted in bearings 45. Two handles 46 and 47 are fixed to the offset rod, one to each end and they project at right angles to the same.

A screw 48 projects through a bushing 49 which has an internal thread therein and which is fastened in the casing 13. Screw 48 serves to limit the movement of the lever 23. Screw 50 projects through a threaded opening in the bottom of the casing 13 and serves to limit the downward movement of the hoist arm 17. In bracket 16 is a set screw 51 which engages with member 52 which is made of felt or some substance which will deaden the sound and which tends to prevent the rebound that would be caused by the coming together of two solid bodies. Member 52 is mounted on the casing 13. By means of screw 51 the horizontal position of hoist arm 17 may be adjusted so as to force it into line with the main guides 10.

35 A projection 53 integral with the cam wheel 15 engages with the bracket 16 and serves to connect the two together. An adjustable screw 54 which engages with an internal thread in an opening through projection 53 is used to adjust the relative positions of cam 15 and bracket 16 so as to take care of manufacturing variations.

40 A spur guide 55 is mounted on the casing 13 so as to be in line with hoist arm 17 when it is in its horizontal position.

The eccentric screw 34 projects through one side of the casing 13 and the dog 32. As the position of the bracket 16 is altered relative to the main guides 10 by means of screw 51, the position of the dog 32 may be altered by means of the eccentric screw 34 so that the dog 32 will always closely engage projection 35 when the hoist arm is in its horizontal position. The connecting rods 38 and 43 are so constructed that the distance between the members which they connect may be varied.

45 After the device has been adjusted by means of the adjusting screws mentioned, the operation of the device is as follows:

50 When the hoist arm 17 is in a horizontal position and it is desired to lower it, the lever 44 is operated so as to raise rod 43.

55 This relieves the pull on lever 37 and lever 23 which are fixed to the shaft 22. The

tension in spring 27 applied to lever 23 causes shaft 22 to rotate until lever 23 is stopped by set-screw 48. As lever 23 rotates, the tension in the spring 27 is reduced, and at the same time, rod 31 is forced 70 in the direction of dog 32 and rotates the same about its axis so as to disengage it from projection 35 and thus releases the hoist arm. The reduction of the tension of spring 27 decreases the negative moment 75 about the axis of the shaft 14 so that the positive moment created by the hoist arm overbalances it and consequently the hoist arm descends. After the hoist arm 17, has passed through a small arc, the moment 80 created by the hoist arm about the axis of the shaft 14 which is also the cam axis, decreases since the line through which its weight acts due to the force of gravity moves toward the shaft 14. When the hoist arm 17 descends, it rotates the cam wheel 15. As the cam wheel 15 rotates, the tension in spring 27 increases. At the same time, however, due to the shape of cam wheel 15 the moment arm through which the force of the spring 27 is applied to shaft 14, decreases fast enough so that the moment due to the spring is slightly less than the moment due to the hoist arm for a given arc of rotation. After the hoist arm 17 has passed through this arc in which the moments are unbalanced, it reaches an arc in its path where the moments are again balanced due to the shape of cam 15. If the hoist arm 17 has sufficient momentum 100 on reaching this arc of balanced moments, it will continue to the limit of its movement where it will be stopped by screw 50. Since its momentum decreases through this arc, it will not strike screw 50 with any considerable force and the rebound will not be appreciable. If the hoist arm is stopped anywhere in this arc where the moments are balanced it will remain in that position.

105 After the hoist arm 17 is lowered, the ticket 20 is inserted into the ticket holder 19. The lever 44 is then operated to draw down rod 43 which rotates the bell crank 41 and through rod 38 revolves lever 37 which rotates shaft 22 and lever 23 thus 115 increasing the tension of spring 27. This increases the moment about the cam axis created by the spring 27 and overbalances the moment created by the hoist arm 17. The hoist arm begins to ascend and as it 120 ascends, the positive moment around the shaft 14 due to its weight increases. Also, as the hoist arm ascends, the cam wheel 15 rotates, and the point at which the tape 28 is fixed to the cam wheel 15, moves toward lever 23, thus decreasing the tension of spring 27. As the tension of spring 27 decreases, the moment arm, through which it acts on shaft 14, increases in length fast enough so that the negative moment around 130

the shaft 14, due to the spring 27, is always slightly more than the positive moment due to the weight of the hoist arm 17. This causes said hoist arm 17 to ascend until 5 set screw 51 engages with the felt stop 52 when the hoist arm 17 is in its horizontal position. At this point, dog 32 engages with projection 35 on the bracket 16 and prevents any rebound which might occur if 10 the moment developed by the spring 27 was enough greater than that due to the hoist arm 17, to throw screw 51 against member 52 with considerable force.

After the hoist arm 17 reaches its horizontal position, the ticket 20 is carried along the hoist arm into the spur guide 55 and then into one of the main guides 10 by the trolley arm 21.

What is claimed is:

20 1. In combination with a ticket distributing system, a ticket hoist comprising a casing, a hoist arm rotatably mounted in said casing, and means connected with said hoist arm to overbalance or underbalance the moment about the hoist arm axis due to the weight of said hoist arm to operate the same.

25 2. A ticket hoist comprising a casing, a shaft journalled in said casing, a hoist arm fixed to said shaft, and means connected to 30 said hoist arm to overbalance or underbalance the moment about said shaft created by said hoist arm to operate the same.

35 3. In combination with a ticket distributing system, a ticket hoist comprising a casing, a hoist arm rotatably mounted in said casing, means connected to said hoist arm to balance the moment about said hoist arm axis due to the weight of said hoist arm when it is in certain positions, and means to 40 disturb said balance to operate said hoist arm.

45 4. In combination with a ticket distributing system, a ticket hoist comprising a casing, a shaft journalled in said casing, a hoist arm fixed to said shaft, and manual operating means connected to said hoist arm to overbalance or underbalance the moment about said shaft created by said hoist arm.

50 5. A ticket hoist comprising a casing, a shaft journalled to said casing, a hoist arm fixed to said shaft, a cam wheel rotatably mounted on said shaft and connected to said hoist arm, a spring connected to said cam, and means for varying the tension of said 55 spring to develop a moment about said shaft that is greater than or less than the amount due to the weight of said hoist arm to operate the same.

60 6. A ticket hoist comprising a casing, a shaft pivoted in said casing, a hoist arm fixed to said shaft, means connected to said hoist arm to create a counter-moment about said shaft to balance the moment due to the weight of said hoist arm when it is in certain 65 positions, means to lock the hoist arm

in its horizontal position, and means to vary the counter-moment and release the hoist arm.

7. A ticket hoist comprising a casing, a shaft rotatably mounted in said casing, a hoist arm fixed to said shaft, a cam wheel rotatably mounted on said shaft and adjustably connected to said hoist arm, and manual operating means connected with said cam wheel to vary the moment about said shaft to operate said hoist arm.

8. A ticket hoist comprising a casing, a shaft mounted on said casing, a hoist arm fixed to said shaft, a cam wheel rotatably mounted on said shaft and adjustably connected to said hoist arm, a spring connected to said cam wheel, and means to vary the tension of said spring to vary the moment about said shaft created by said spring to operate said hoist arm.

85 9. A ticket hoist comprising a casing, a shaft mounted in said casing, a hoist arm fixed to said shaft, a cam wheel rotatably mounted on said shaft and adjustably connected to said hoist arm, a spring connected to said cam wheel, and means for decreasing the tension of said spring to increase the moment about said shaft axis created by said hoist arm to cause the said hoist arm to rotate downward about said shaft.

95 10. A ticket hoist comprising a casing, a shaft mounted in said casing, a hoist arm fixed to said shaft, a cam wheel rotatably mounted on said shaft and adjustably connected to said hoist arm, a spring connected to said cam wheel, and means for increasing the tension of said spring to overbalance the moment about said shaft axis created by said hoist arm to cause the said hoist arm to rotate upward about the axis of said shaft.

105 11. A ticket hoist comprising a casing, a shaft mounted in said casing, a hoist arm fixed to said shaft, a cam wheel rotatably mounted on said shaft and provided with adjustable means for making engagement with said hoist arm, a spring connected to said cam wheel, and means to increase the tension of said spring to increase the moment about said shaft axis to cause the cam and hoist arm to rotate about said shaft, 110 said cam serving to increase the moment about said shaft axis as the tension of said spring is decreased by the rotation of said cam so that the moments about said shaft axis do not become balanced until said hoist 120 arm has been rotated through the desired angle.

12. A ticket hoist comprising a casing, a shaft mounted in said casing, a hoist arm fixed to said shaft, a cam wheel rotatably mounted on said shaft and provided with adjustable means for making engagement with said hoist arm, a spring connected to said cam wheel, and means to decrease the tension of said spring to decrease the mo-

- ment about said shaft due to said spring to cause said cam and said hoist arm to rotate about said shaft, said cam wheel serving to decrease the moment about said shaft axis as 5 the tension of said spring is increased and the moment due to said hoist arm decreased due to said rotation so that the moments are not balanced until said hoist arm has been rotated to the desired angle.
- 10 13. A ticket hoist comprising a casing, a shaft mounted in said casing, a hoist arm fixed to said shaft, a cam wheel rotatably mounted on said shaft provided with adjustable means for making engagement 15 with said hoist arm, a spring connected to said cam, and means to vary the tension of said spring to vary the moment about said shaft axis due to said spring to cause the said cam and hoist arm to rotate about said 20 shaft, said cam being so designed that it varies the moment due to said spring sufficient to prevent balance of the moments about said shaft until said hoist arm has been moved to the desired angle.
- 25 14. In combination with a ticket distributing system, a ticket hoist comprising a casing, a shaft journaled in said casing, a hoist arm having a projection thereon fixed to said shaft, a cam wheel rotatably 30 mounted on said shaft and provided with adjustable means for engaging said hoist arm, a screw fastening means attached to the periphery of said cam wheel, a second shaft journaled in said casing, a plurality 35 of levers fixed to said second shaft, one inside and the other outside of said casing, a projection the shape of an arc of a circle integral with said inside lever, a screw fastening means on said lever projection, a link 40 comprising a spring with a tape connected to each end for connecting the screw fastening means on said lever projection to screw fastening means on said cam wheel, an adjustable screw carried by said casing to limit the 45 movement of said inside lever, a system of adjustable connecting rods and levers connected to said outside lever for operating the same to vary the tension of said spring, a set screw carried by said hoist arm to limit its 50 upward movement, a second set screw carried by said casing to limit the downward movement of said hoist arm, and an adjustable locking means carried by said casing and operated by said inside lever comprising 55 a dog and adjustable connecting rods attached thereto and detachably connected to said inside lever, said dog serving to engage with said hoist arm projection to retain said hoist arm in its horizontal position until 60 said dog is raised by the operation of said inside lever to reduce the tension of said spring.
15. In a ticket distributing system, a guide, means pivotally supporting a portion of said guide, and means to change the 65 moment about the pivot for changing the position of said portion.
16. In a ticket distributing system, a guide, a pivot on which a portion of the guide is balanced, and means for unbalancing said 70 portion to control the movement thereof.
17. In a ticket distributing system, a shaft, an arm fixed thereto, and means to change the moment about said shaft for operating 75 said arm.
18. In a ticket distributing system, a shaft, an arm fixed thereto, and means to create a counter-moment about the shaft to balance the moment caused by the arm while it is descending.
19. In a ticket distributing system, a hoist arm, and means comprising a system of varying moments to move said hoist arm.
20. In a ticket distributing system, a casing having a shaft journaled therein, an arm 85 rotatably mounted on said shaft, and means located in said casing and operable conjointly with said arm to cause said arm to move in an arcuate path.
21. A conveyor comprising a movable 90 spur track, motive means therefor ineffective to move said track when in an article receiving position and operator controlled means for rendering said motive means effective to move said track.
22. A conveyor comprising a movable track, operator controlled means for starting said track towards an article receiving position, and means independent of said first 95 means whereby said track remains in said position.
23. A conveyor comprising an article carrier, motive means therefor ineffective to move said carrier when in an article receiving position, and operator controlled means for 100 rendering said motive means effective to move said carrier.
24. The method wherein a track is movable between receiving and discharging positions which comprises starting said track towards the receiving position and thereafter applying motive power independent of the operator for continuing the movement of said track.
25. The method wherein a track is movable between receiving and discharging positions which comprises, starting said track towards either position and thereafter applying motive power independent of the operator for continuing the movement of said 115 track.
- In witness whereof, I hereunto subscribe my name this 14 day of March A. D., 1921.
- CHARLES L. VAN INWAGEN.
